(57) **CLAIM**

I claim the ornamental design for a storage tote, as shown and described.

DESCRIPTION

FIG. 1 is a front perspective view of a first embodiment of my design;

FIG. 2 is a front view thereof;

FIG. 3 is a rear view thereof;

FIG. 4 is a left side view thereof, the right side being a mirror image thereof;

FIG. 5 is a top view thereof;

FIG. 6 is a bottom view thereof; and,

FIG. 7 is a rear perspective view thereof.

The dashed lines in the figures form no part of the claimed design. The long-short dashed lines that abut a claimed surface represent an unclaimed boundary between claimed and unclaimed surfaces and form no part of the claimed design. All other surface(s) or portion(s) of my design not shown in the figures or otherwise described in the specification, such as the interior of the storage tote, form no part of the claimed design.
